UNITED STATES PATENT OFFICE.

JOSEPH DUDASH, OF PHILADELPHIA, PENNSYLVANIA.

SPEED-BOAT.

1,112,057.

Specification of Letters Patent. Patented Sept. 29, 1914.

Application filed October 8, 1913. Serial No. 794,138.

To all whom it may concern:

Be it known that I, JOSEPH DUDASH, a subject of the Apostolic King of Hungary, residing at Philadelphia, in the county of 5 Philadelphia and State of Pennsylvania, have invented certain new and useful Improvements in Speed-Boats, of which the following is a specification.

This invention has relation to what is generally termed motor-boats and has more particular relation to the type of boats designated speed-boats.

The principal object of the present invention is to provide a speed-boat so arranged 15 and constructed, that the speed thereof may be considerably increased without adding to the cost of maintenance and operation.

A further object of the present invention, is to provide a speed-boat in which the keel 20 thereof is operatively equipped with a screw-propeller which parallels the keel, the shaft of which is driven from a point approximately amidship.

Other and further objects of the present 25 invention reside in the providing of general details of construction and arrangement of parts as will hereinafter more fully appear.

The invention consists of the improvements hereinafter described and finally 30 claimed.

The nature, characteristic features and scope of the invention, will be more fully understood from the following description taken in connection with the accompanying 35 drawings forming part hereof and in which:

Figure 1, is a view in longitudinal section of the speed-boat embodying the invention, and Fig. 2, is a view in cross section taken upon the line 2—2 of Fig. 1.

40 In the drawings the keel 10, of the boat 11, is shown as slanting from stem to stern and the bow of the boat is shown as being generally tapered as at 12. Thus constructed, the boat will run with the greatest portion 45 of its bow out of the water in contradistinction from having its bow submerged and cutting the water for a purpose to be presently described. Suspended from the keel 10, and extending from a point approximately amidship to a point adjacent the stern of the boat is a screw-propeller 13. The shaft 14, of the propeller 13, parallels the keel 10, of the boat and is rotatably supported in bearings 15, and 16 of hangers 17,

and 17^a, which hangers are secured in any 55 suitable manner to the boat-bottom.

In order to prevent water entering the bearings 15, and 16, stuffing boxes 18, are present. In order to take up any end-thrust of the shaft 14, in reversing the course of the 60 boat a thrust bearing 19, is present within the bearing 16. Partially inclosing the screw-propeller is a generally cylindrical casing 20, which is open fore and aft, so that as the boat is being propelled along, water may 65 enter the casing 20, with sufficient pressure so that the propeller 13, efficiently acting thereagainst may propel the boat forwardly at high speed assuming that the motor which drives the propeller is running at a proportionate rate of speed. In this connection it is to be observed that the motor 21, which drives the propeller-shaft 14, and which may be an internal combustion engine or electric motor or other type of motor force is located 70 adjacent the bow of the boat and the driving shaft thereof is connected with the propeller-shaft by means of a driving rod 22. Universal joints 23, are present as shown in the drawings for transmitting proper motion to 75 the propeller-shaft.

Shown as being bolted or otherwise secured to the bottom of the boat and to the hanger 17, is a two-part casing 24, of generally elliptical cross section for inclosing that 85 portion of the connecting rod 22, and propeller-shaft 14, which would otherwise be exposed to the water. By constructing this casing 24, of elliptical cross section, very little resisting surface is offered the water in 90 the propulsion of the boat. By placing the motor 21, in the bow of the boat and connecting the same as shown and described with the propeller 13, the boat both at the stern and amidship is roomy and free of 95 obstruction which obviously is advantageous. By arranging the keel 10, at an angle as shown and described and cutting away the bow as also described, little or no obstruction is offered water at the point opposite 100 the forward part of the casing 20, and it may readily enter said casing. If the bow was constructed to cut the water in the propulsion of the boat the water would be spread to the port and starboard of the boat 105 and away from the open end of the casing. By also forming the keel and bow of the boat as shown, the boat will more readily

ride swells and breakers thus saving wear and tear upon the propeller and its complementary parts.

What I claim is:

- 5 In a speed-boat, a motor, hangers secured to the boat-bottom, a screw-propeller operationally mounted between said hangers, a generally cylindrical casing open fore and aft for partially inclosing said screw-propeller
- 10 secured to the boat-bottom, a driving rod connecting said motor and screw-propeller,

said driving rod penetrating the boat-bottom and a casing of generally elliptical cross section for inclosing that part of the driving rod exposed to the water.

In testimony whereof, I have hereunto signed my name.

JOSEPH DUDASH

In the presence of—

HELEN M. BYRNE,
WILLIAM J. JACKSON.
